US00D979549S

(12) **United States Design Patent** (10) Patent No.: **US D979,549 S**
(45) Date of Patent: ** *Feb. 28, 2023

(54) **MOBILE PHONE**

(71) Applicant: **HONOR DEVICE CO., LTD.**,
Guangdong (CN)

(72) Inventor: **Linlin Wang**, Shenzhen (CN)

(73) Assignee: **HONOR DEVICE CO., LTD.**,
Shenzhen (CN)

(*) Notice: This patent is subject to a terminal disclaimer.

(**) Term: **15 Years**

(21) Appl. No.: **29/825,267**

(22) Filed: **Jan. 31, 2022**

Related U.S. Application Data

(63) Continuation of application No. 29/724,319, filed on Feb. 14, 2020, now Pat. No. Des. 942,437.

(30) **Foreign Application Priority Data**

Aug. 16, 2019 (CN) 201930447672.0

(57) **CLAIM**

The ornamental design for a mobile phone, as shown and described.

DESCRIPTION

FIG. 1 is a back perspective view of a mobile phone, showing my new design;

FIG. 2 is a front view thereof;

FIG. 3 is a back view thereof;

FIG. 4 is a bottom view thereof;

FIG. 5 is a top view thereof;

FIG. 6 is a left side view thereof; and,

FIG. 7 is a right side view thereof.

The broken lines in drawings show portions of the mobile phone that form no part of the claimed design.

1 Claim, 5 Drawing Sheets
